UNITED STATES PATENT OFFICE.

JOHN FULGER, OF ALACHUA, FLORIDA.

DESIGN FOR A BED.

45,190.

Specification for Design.

Patented Feb. 3, 1914.

Application filed November 10, 1913. Serial No. 800,235. Term of patent 7 years.

To all whom it may concern:

Be it known that I, JOHN FULGER, a citizen of the United States, residing at Alachua, in the county of Alachua and State of Florida, have invented a new, original, and ornamental Design for Beds, of which the following is a specification, reference being had to the accompanying drawing, forming a part thereof, in which a perspective view of the bed is shown.

I claim:

The ornamental design for a bed, as shown.

In testimony whereof I affix my signature, in the presence of two witnesses.

JOHN FULGER.

Witnesses:
